UNITED STATES PATENT OFFICE.

JOHN WILLIAMS PURNELL, OF MORRISTOWN, TENNESSEE, ASSIGNOR OF ONE-HALF TO
E. B. FISHER, OF MORRISTOWN, TENNESSEE.

ELECTRIC STOVE.

1,229,786.

Specification of Letters Patent. Patented June 12, 1917.

Application filed January 12, 1917. Serial No. 141,993.

To all whom it may concern:

Be it known that I, JOHN WILLIAMS PURNELL, a citizen of the United States, residing at Morristown, in the county of Hamblen, State of Tennessee, have invented a new and useful Electric Stove; and I do hereby declare the following to be a full, clear, and exact description of the invention, such as will enable others skilled in the art to which 10 it appertains to make and use the same.

This invention is an electric stove to be used for heating or cooking purposes.

Its principal object is to provide a stove with a supporting structure cast out of fire 15 proof material and with a supplementary fire proof support for the heating element that can be removed from the main supporting structure for cleaning purposes.

Another object of the invention is to provide a support for the heating elements from 20 which these elements can be removed for cleaning or for renewal after having been broken or damaged.

A third object of the invention is to provide a device of this kind wherein the main 25 supporting structure carries means for attachment to the electrical source of supply, so that electrical energy can be transmitted to the heating elements by a system of separable connections.

As a fourth object, provision is made for the manual operation of a system of levers for raising the supplementary supporting structure containing the heating element 30 vertically out of the main supporting structure.

From the structure illustrated in the drawings, practical application may require some deviations, and the right is claimed to make any that are comprehended in spirit by the 40 appended claims.

The same numerals of reference designate the same parts throughout the several figures, wherein:

Figure 1 is a plan view of the invention.

Fig. 2 is a section on line 2—2 of Fig. 1.

Fig. 3 is a section on line 3—3 of Fig. 1.

Fig. 4 is a section on line 4—4 of Fig. 1.

Fig. 5 is a perspective view of the end connections for the heating element. These 50 connections contact with the connections carried by the main structure.

Fig. 6 is a perspective view of one of the intermediate connectors for the heating elements.

Fig. 7 is a perspective view of one of the 55 bell crank levers used in raising the supplementary supporting structure.

The main supporting structure is designed to be cast out of fire clay or some fire-resisting material, or it may be made 60 out of porcelain. It has the longitudinal legs 1 and the end legs 2. On the inside, at a certain distance below the upper edges, the ledges 3 and 4 are cast, and these ledges serve to hold the supplementary supporting structure 5. On the outer face of one of the legs 1, the studs 6 are attached, their shoulders 7 abutting the outer face of 1, and their shanks penetrating 1. Set in the inner surface of 1 are the angular connecting strips 8. These strips are designed to be flush with the inner surface of 1, and have holes through which the shanks of 6 65 protrude. When the nuts 9 are attached to the shanks of 6, they hold the studs 6 firmly in position on 1, and provide electric 70 contact from 6 to 8. The contacting strips 8 are embedded in the surface of 1 for substantially their whole length; the ends remote from 6, however, are bent back on 75 themselves forming the U-shaped connectors 10.

On the end legs 2, slots 11 are formed to provide free movement for the arm 12 of the bell crank levers used for lifting the 85 supplementary supporting structure 5. In addition to 12, the bell crank levers have the cylindrical ends 13, the studs 14, and the arms 15, as integral parts thereof, and they further have the conical shaped end 90 pieces 16 screwed on to threaded studs 17, which are integral parts of the arms 15. Angle plates 18 are attached (one on each side of slots 11) to the leg 2 by the screws 19 and their attendant nuts 20, and the 95 ends of these plates are provided with eyes which engage the studs 14 of the bell crank levers and give said levers a pivotal mounting on the legs 2.

The supplementary supporting structure 100 5 has the upturned edges 21, 22, and 23. From each of the edges 21 and 22, a series of transverse ribs emanate, the ribs 24 of the series emanating from 22 alternating with the ribs 25 of the series emanating 105 from 21. The central transverse rib 25^a is wider than its neighbors and is made so as to give increased strength to the supple-

mentary supporting structure 5. The upturned edges 21, 22 and 23 and, the ribs 24 and 25 are integral parts of the supplementary supporting structure 5. The ribs 5 emanating from either 21 or 22 approach close to but do not touch the opposite side, and these ribs, therefore, form a series of recesses which so connect as to form a zig 10 zag compartment in which the heating elements are held. At the end remote from its junction with the upturned edges 21 and 22, any one of the ribs 24 or 25 is straddled at its end by an intermediate connector for the heating elements. Each 15 intermediate connector comprises the channel member 26 with a post 27 made integral with its flanges. Each post has a hole 28 to receive an end of one of the heating elements and a screw 29 for holding said end in firm contact with said hole. On both 20 the ribs 24 and the ribs 25 the free ends are undercut and in this undercut portion of the ribs, the webs 30 of the channel pieces 26 rest. The heating elements 31 are 25 placed one each in the recesses formed by ribs 24 and 25 and are electrically connected in series by means of the intermediate connectors formed by the channel pieces 26 and their attendant binding 30 posts. The two end heating elements (in the recesses formed by 23 and 24) have their ends, which are adjacent to the edge 22, connected to the binding posts 32 of the angle plates 33. The angle ends of the 35 plates 33, after having passed through rectangular slots 34 (formed in the upturned side 22 at the bottom of the recesses formed by ribs 24 and sides 23) engage the sides 25 on the exterior and are in a position to 40 contact with the U-shaped connectors 10.

The supplementary supporting structure 5 has a projecting ledge 35 at the bottom of its side 22, and this ledge is designed to engage the ledge 3 on the back leg 1 and 45 both 3 and 35 are cut away at the point where the connector 10 is positioned, the ledge 35, so that the supplementary supporting structure may be removed without interfering with the connector 10 and the 50 ledge 3, so that the angle connecting strip 8 may be easily placed in position.

When this device is put in service, the studs 6 are designed to receive the conventional electric attachment plug, which, 55 when connected with a source of electrical supply, will enable the heating elements 31 to be supplied with electric current. Beginning at one of the studs 6, the circuit is from the shank of that particular stud to 60 its attendant angular connecting strip 8, thence to the U-shaped connector which is integral with that particular strip, thence to the angle plate 33 contacting with the connector 10, thence through the first heating 65 element, thence one of the intermediate

connectors 26, thence to the second heating element, and continuing alternately from an intermediate connector to a heating element, and reaching the second stud 6 by traveling reversely a second and similar path by which it left the first stud. 70

The cylindrical ends 13 of the bell crank levers are adapted to normally contact with the bottom of the supplementary supporting structure 5, each being held in position by the overbalancing weight of its conical end piece 16. It is thus possible to remove the supplementary supporting structure from the main structure by any pressure applied to the arms 15, which will operate to raise 75 the cylindrical ends 13 and with them supplementary supporting structure 5. This operation disconnects the heating elements from the source of electrical supply by separating the contacting surfaces of the angle plates 33 and their U-shaped connectors 10. The heating elements may also be removed 80 from the supplementary supporting structure by disengaging the intermediate connectors from the undercut ends of the transverse ribs and by tilting the angle plates 33 sufficiently to disengage them from the slots 34. It will be seen that the device as thus 85 separated into its concomitant parts, which may be readily cleaned, and, if any of the heating elements are broken or damaged, the damaged elements may be easily released from the intermediate connectors to which they are joined by loosening the screws 29, whereupon new heating elements may be 90 substituted. 95

The invention having been set forth, what is claimed as new and useful is:—

1. In an electric stove for cooking or heating, a main supporting structure having electrical connectors embedded in its surface and terminating at one end in resilient connections for transmitting current to the heating elements, a supplementary supporting structure for the heating elements, said supplementary structure having a series of ribs so disposed as to form a zig-zag recess wherein the heating elements lie, a series of heating elements interposed between said ribs, channel-shaped connectors engaging 105 said ribs and electrically connecting the heating elements, angle plate connectors for electrically joining the heating elements with the connectors on the main supporting structure, and bell-crank levers pivotally supported on the main structure and operative so as to lift out the supplementary supporting structure and thereby disengage the connections between the heating elements and the source of electrical supply. 110

2. In an electric stove for cooking and heating; the combination with a main supporting structure and a supplementary supporting structure; the former having electrical connectors attached thereto, the latter 120

- having a series of transverse ribs; of a series of individual heating elements interposed between the ribs; channel shaped connectors engaging the ends of the ribs and electrically connecting the heating elements in sequence; and angle plate connectors electrically connecting the heating elements with connectors on the main supporting structure.
- 10 3. In an electric stove for cooking and heating; a main supporting structure having electrical connectors on the inner face of one side, one connector at each end thereof, a terminal contact forming a part of each 15 of said connectors; a supplemental supporting structure, provided with a series of transverse ribs, each alternate rib having its end unattached from the opposite sides of the supplemental structure; a series of individual heating elements interposed between 20 said ribs; channel shaped connectors engaging the alternate unattached ends of the ribs and electrically connecting said heating elements in sequence; and angle plate connectors, 25 one connected to one end of each end heating element, thereby electrically connecting the end heating elements and said terminal contacts of the connectors on the main supporting structure.
4. In an electric stove for cooking and heating, a main supporting structure having electrical connectors seated in the inner face of one side and terminating at one end in resilient connections for transmitting current to the heating elements, a supplementary supporting structure for the heating elements, said supplementary structure having a series of ribs so disposed as to form a zig zag recess for the reception of the heating elements, a series of heating elements interposed between said ribs, channel-shaped connectors engaging said ribs and electrically connecting the heating elements, and angle plate connectors for electrically joining the heating elements with the connectors on the main supporting structure. 30 35 40 45

In testimony whereof I have signed my name to this specification in the presence of two subscribing witnesses.

JOHN WILLIAMS PURNELL.
